UNITED STATES PATENT OFFICE.

JAMES D. PARKER, OF KANSAS CITY, KANSAS.

VENTILATING FAN.

Application filed October 28, 1925. Serial No. 65,312.

The invention relates to improvements in fans for ventilating buildings and mines and circulating air for heating buildings and drying lumber, grain, coffee and the like.

5 And more particularly to certain improvements in a particular type of fan commonly known as a cone or conical fan and sometimes called a conical hemispherical fan as the cutting edges of the blades are frustum shaped and the discharge edges are spherical.

The fan as heretofore built has not attained that high state of perfection desired by the applicant, owing to the employment 15 of a hub comprising a hollow conical disk integrally connected at its apex to a sleeve which in turn is integrally connected to a disk approximately flat but slightly spherical. The base or hollow side of the conical portion of the disk is presented to the advancing air that is drawn by the suction side 20 of the fan and creates not only a resistance, but also a back current commonly called back lash. When the air passes over the 25 conical shaped disk it must, after rolling through the space between the two disk portions of the hub into which the blades do not cut, encounter the flat spherical disk of the hub, and then after the air has completely 30 passed the hub there is a back current or back lash of the air against the flat spherical disk portion of the hub. These back currents or back lash not only lowers the efficiency of the fan by reducing the volume 35 of air the fan would move were the hub fan shaped, but a considerable undesirable noise is set up by the back current or back lash of the air.

The present invention has provided a fan 40 that is all fan from the sleeve portion of the hub outwardly, by removing the conical disk and the flat spherical disk and providing a hub that is also a fan from the sleeve portion of the hub outwardly.

45 A further improvement in the fan is accomplished by extending the inner ends of the blades and causing them to meet the sleeve portion of the hub, thus removing and eliminating all reverse currents and back lash, and also all objectionable noise.

With these and other objects in view, the invention consists in the features of construction, combinations, and arrangements

of parts hereinafter set forth and more particularly pointed out in the appended claims, 55 the accompanying drawings illustrating a form of the improved fan that has proven all that is claimed for it.

In the drawings:—

Fig. 1 is a view in elevation of the improved fan with certain parts not in view shown in dotted lines in order to illustrate the general construction and the relations of the old parts to the new.

Fig. 2 is a view of the suction and intake 60 side of the fan.

Fig. 3 is a view of the discharge and delivery side of the fan.

Fig. 4 is a perspective view of the fan illustrating the blades extended and meeting 70 the sleeve part of the hub, and the clear space through the hub for the passage of air.

Fig. 5 is a view in side elevation of the improved hub of the fan.

Fig. 6 is an end view of one wing of the 75 hub and a slightly angular end view of a second wing, the remainder of the hub being broken away.

Fig. 7 is an end view of the hub.

Fig. 8 is an end view of the hub with all 80 but one of the wings broken away.

The frame 1 bearing boxes 2, ring shaped yokes 3, brackets 4, auxiliary hub 5, radial arms 6, ring 7, and shaft 8 are all of common and well known construction, the pulley 85 9 being shown merely as one means of driving, as it is often replaced by other driving means, as direct connected motors, engines and the like, the parts being illustrated merely to show an example of common 90 usage.

The hub 10 is rigidly mounted on the shaft 8, the set screw 11^a being illustrated as one means of securing the hub to the shaft.

The hub 10 is bored to receive the shaft 95 8 and comprises the elongated cylindrically shaped sleeve 11, the wings 12 arranged in pairs spirally, one on each end of the sleeve 11 and the rectangular wings 13, the sleeve and all the wings being integral and forming the hub.

The wings 13 are flat and rectangular in shape, and meet and rest upon and cross the sleeve 11 at the longitudinal center of the sleeve and at this point are disposed in 165 radial lines from the axis of the hub. The

ends of the wings 13 converge considerably outwardly in opposite directions from the axis of the hub, and the wings 12 connect the wings 13 to the sleeve 11 so that no air can pass underneath the wings and so that the wings of the hub actually act as fan blades.

The wings 13 are provided with the holes 14 for the purpose of bolting the blades 15 and braces 16 and 17 thereto by the bolts 18.

The ring 7 is disposed concentrically to the shaft 8, the radial lines of the ring forming right angles with the shaft, the hub 10 being positioned on the shaft at some distance from the ring.

The braces 16 are approximately straight and connected rigidly from the ring to the near end of the hub 10 forming an angle converging outwardly at the hub from the axis of the shaft to the ring.

The braces 17 connect rigidly from the outward end of the hub 10 to the ring 7 and lay approximately each in a common plane with the axis of the shaft but bow considerably outwardly, the blades 15 being secured to the braces 16 and 17.

The ends of the blades 15 are spaced apart at the ring 7 by the braces 16 and 17 but overlap at and near the hub 10 the latter ends of the blades reaching and meeting the sleeve 11.

The fan rotates in the direction of the arrow Fig. 3, the edges 19 of the blades 15 being held rigidly straight by the braces 16, and cutting the air that is to be moved, the edges 20 of the blades 15 being held rigidly in a bowed position by the braces 17 and pushing the air through and from the fan, the blades being in action to the sleeve portion 11 of the hub 10 so that there is no reverse current or back lash at the center of the fan.

The blades 15 and braces 16 and 17 at and near the ring 7 as illustrated in the drawing and described hereinbefore are not new and not intended to be covered by the appended claims.

The hub 10 comprising the sleeve 11, the wings 12 and 13, and the blades 15 and braces 16 and 17 at and near the hub 10 are new and have provided a great improvement in the performance of the fan.

By providing an improved hub and extending the blades 15 and braces 16 and 17 to the sleeve portion of the hub 10, the efficiency of the fan is materially increased and all back currents, back lash and objectionable noise has been eliminated.

Having described my invention, what I

claim as new and desire to secure by Letters Patent, is:—

1. In a fan, a hub and ring spaced apart and in axial alignment, said hub comprising a cylindrically shaped sleeve provided with a plurality of spirally disposed wings, the periphery of each spirally disposed wing forming a straight line crossing said cylindrically shaped sleeve near the center of the length of said sleeve and converging laterally from the axis of said hub at each end thereof, a flat rectangularly shaped wing mounted on each of said spirally shaped wings, each of said flat rectangularly shaped wings disposed radially from the axis of said sleeve near the center of the length of said wing and said sleeve, the ends of said rectangular wings converging in opposite directions from the axis of said sleeve, said sleeve and said spiral wings and said flat rectangular wings formed integrally, a blade secured to each of said rectangularly shaped wings, the cutting edge of each blade disposed in a straight line from said wing to said ring and secured thereto, the discharge edge of each of said blades bowed outwardly and connected to said ring, and said blades conforming to the shape of said ring at their outer ends.

2. In a fan, a hub comprising a cylindrically shaped sleeve provided with a plurality of wings, said wings disposed spirally around and along said hub, said wings changing to a flat rectangular shape, blades secured to said rectangular shaped wings and leaning angularly therefrom around the axis of said hub, the outer ends of said blades supported concentrically around the axis of said hub, the cutting edges of said blades forming a frustum shape and the discharge edges of said blades forming a spherical shape.

3. A fan provided with a plurality of blades, one end of said blades disposed concentrically to the axis of rotation of said fan, in combination with a cylindrically shaped hub disposed concentrically to the axis of rotation of said fan, said hub comprising a sleeve provided with spirally shaped wings, said spirally shaped wings having mounted thereon flat rectangularly shaped wings, said blades secured at their opposite ends to said rectangularly shaped wings, the cutting edges of said blades forming a frustum shape, and the discharge edges of said blades forming a spherical shape.

JAMES D. PARKER.
